US0D1075020S

(12) **United States Design Patent** (10) **Patent No.:** **US D1,075,020 S**
(45) **Date of Patent:** **** May 13, 2025**

(54) **BIOSIGNAL MEASURING DEVICE**

(71) Applicant: **HHS CO., LTD.**, Ulsan (KR)

(72) Inventors: **Hyung Seob Han**, Ulsan (KR); **Yong Seok Han**, Ulsan (KR); **Kyoung Young Song**, Ulsan (KR)

(73) Assignee: **HHS CO., LTD.**, Ulsan (KR)

(**) Term: **15 Years**

(21) Appl. No.: **29/820,553**

(22) Filed: **Dec. 22, 2021**

(51) **LOC (15) Cl.** **24-02**

(52) **U.S. Cl.**

USPC **D24/186**

(57) **CLAIM**

The ornamental design for a biosignal measuring device, as shown and described.

DESCRIPTION

FIG. 1 is a front, left side perspective view of a biosignal measuring device, showing our new design;

FIG. 2 is a rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
